APPARATUS FOR CEMENTING WELL
CASINGSFrancis Hampton Lee, San Pedro, Calif., assignor
to Baker Oil Tools, Inc., Vernon, Calif., a cor-
poration of California

Application February 24, 1947, Serial No. 730,345

14 Claims. (Cl. 166—1)

1

This invention relates to apparatus adapted to form part of a casing, liner or similar conduit string, and is particularly directed to apparatus of the type embodying side ports which can be opened and closed to determine the passage of fluids between the interior and the exterior of the apparatus.

An object of the present invention is to provide side ported apparatus adapted to form part of a casing string, in which the side ports can be both opened and closed in response to rotation of the casing string in a single direction without the necessity for longitudinally moving such casing string.

Another object of the invention is to provide side ported casing apparatus adapted to form part of a casing string, whose ports are opened and closed by sleeve valve means in response to manipulation of the casing string, without substantial danger of damaging the seals which prevent leakage through the sleeve valve means when it is in closed position.

This invention has other objects and aspects which will become apparent from a consideration of the embodiment shown in the drawings accompanying and forming part of the present specification. This form will now be described in detail, but it is to be understood that such detailed description is not to be taken in a limited sense, since the scope of the invention is best defined by the claims appended hereto.

Referring to the drawings:

Fig. 1 is a longitudinal view, partly in section and partly in elevation, of an apparatus forming part of a casing string with the parts in port closing position.

Fig. 2 is a partial longitudinal section of the apparatus with the parts in port opening position.

Fig. 3 is a view similar to Fig. 2 with the parts in the position to which they have been moved to reclose the ports.

As disclosed in the drawings, a collar apparatus A is connected in the casing string by being attached to upper and lower casing sections B, C. Although specific reference is made in this description to the use of the invention as part of a casing string, it is to be understood that the invention may be installed as a component part of a liner or similar conduit string positioned in a well bore.

The apparatus includes a tubular body 10 formed of several parts, including a lower main tubular member 11 threaded into a coupling 12 screwed on the lower end of an upper tubular

body member 13, whose pin end 14 is attached to the lower end of an upper casing section or collar B. The lower end of the body may be threadedly attached directly to the lower casing section C, or it may be threaded to an interposed swivel D, if desired. Such swivel, in effect, constitutes a lower extension of the body itself, and includes an outer member 15 having an upper shoulder 16 and a lower sleeve 17 threaded thereinto to form an internal circumferential groove 18 in which the upper head 19 of a tubular inner swivel member 20 is received, in order to permit rotation between the outer and inner members 15, 20, but constraining them for conjoint longitudinal movement in both directions. Leakage between the outer and inner members may be prevented by the provision of suitable side seals 21, as in the form of round rubber seal rings, positioned in ring grooves 22 in the head 19 and engageable with the base of the groove 18 furnished by the outer member 15. It is also to be noted that the threaded sleeve 17 may be prevented from becoming disassembled from the outer member 15 by the provision of a suitable weld 23 integrating the two parts.

The body 10 is provided with circumferentially arranged inner ports 24 adapted to be closed by an outer valve sleeve 25, and also by an inner valve sleeve 26 disposed within an annulus 27 formed between the exterior of the body 10 and the interior of the lower portion of the outer sleeve 25. The inner sleeve 26 is designed to move longitudinally along the outer sleeve member 25, but is secured thereto against rotation by a splined connection in the form of a key 28 welded or otherwise attached to the outer sleeve 25 and received within a longitudinally extended keyway 29 in the inner sleeve 26.

The inner sleeve has internal lefthand threads 30 engaging companion external lefthand threads 31 on the tubular body 10 of the apparatus. It is to be noted, however, that these threads extend only along part of both the sleeve 26 and body 10. More specifically, the threads 30 extend upwardly from the lower end of the inner sleeve 26 to a predetermined extent and are engaged with the external threads 31 extending intermediate of the distance between the lower end of the annulus 27 and the inner ports 24. This arrangement is provided, as will be brought out in detail hereinafter, to permit the inner sleeve to move downwardly along the body until the internal and external threads 30, 31 become disengaged, the downward movement of the inner sleeve 26 after such disengagement being limited

by abutting of its lower end with a shoulder 32 on the body 10 defining the lower end of the annulus 27.

The outer sleeve 25 is also threadedly secured to the body 10 above the inner ports 24 by means of external lefthand thread 33 on the body engaging a companion internal thread 34 on the sleeve.

This threaded connection 33, 34 has a different lead from the lead of the threaded connection 30, 31 between the inner sleeve 26 and body 10, in order that relative rotation between the sleeves and body will move the sleeves different distances along the body to control passage of fluids through the inner ports 24. As an example, the lead of the upper threaded connection 33, 34 may be one-half the lead of the lower threaded connection 30, 31, resulting in downward movement of the inner sleeve 26 twice the distance of the outer sleeve 25 upon righthand rotation of the body 10.

As indicated, the sleeves are designed for longitudinal movement along the body 10, as in a downward direction, upon rotation of the entire casing string and body, in order to determine the opening and closing of the inner ports 24. Such relative rotation between the outer sleeve 25 and body 10 and also between the inner sleeve 26 and body, because of the keyed connection 28, 29 of the inner sleeve to the outer sleeve, is determined by a drag device secured to the outer sleeve and extending upwardly along the body. Such drag device includes a lower drag collar 35, which may be integral with the outer sleeve 25, having longitudinal grooves 36 in which the lower ends of outwardly bowed drag springs 37 are received. The springs are prevented from becoming detached from the drag collar 35 by a spring retainer sleeve 38 encompassing the springs 37 and collar and secured, as by the use of welding material 39, to the latter. The upper ends of the springs 37 are secured to an upper collar 40, slideable along the upper body member 13, in a similar manner by an upper sleeve 41 encompassing the collar 40 and springs 37, and welded to the collar 40. These springs are bowed outwardly and are adapted to engage the wall of the well bore in which the casing string is positioned in order to resist rotation of the outer sleeve 25 and the inner sleeve 26 splined thereto.

The device is assembled with the parts occupying the position disclosed in Fig. 1, in which the outer sleeve 25 is in an upper position along the body 10; and in which the inner sleeve 26 also is in its uppermost position, with its inclined head 42 engaging a companion inclined seat 43 on the outer sleeve, to prevent passage of fluids therebetween along the inclined contacting surfaces 42, 43. As assurance against leakage, a suitable seal ring 44 may be mounted in the seat 43 for engagement with the head end of the inner valve sleeve. When in such position, the inner sleeve 26 is disposed across the inner ports 24, leakage between the body 10, inner sleeve 26 and outer sleeve 25 being prevented by side seals 45, 46 on opposite sides of the ports, carried in suitable ring grooves 47 in the body and slidably engageable with both the outer and inner sleeves.

The apparatus, with the inner ports 24 closed, is attached to the upper and lower casing sections B, C, the swivel D preferably being connected to the lower end of the body to form an extension thereof. Such apparatus is then run in the well bore as part of the casing string until the latter has been lowered in the bore to the desired depth. In the event it is desired to discharge cement from

the casing string at some point below the location of the collar A, as through a casing shoe (not shown), circulating fluid may be pumped down the entire length of the casing string for discharge through the shoe and for upward passage through the annulus around the casing string. Following conditioning of the well bore, a charge of cement slurry may be pumped down the casing string for passage through the collar A and for ejection from the shoe, after which it proceeds upwardly through the annulus around the casing string toward the collar A.

After the lower charge of cement has set and hardened, the casing string is rotated to the right from the top of the well bore, which effects rotation only of the upper portion of the casing string attached to the collar A and of the apparatus body 10, because of the swivel connection D between the body 10 and lower casing section C, in order not to disturb the cement slurry placed behind the lower portion of the casing string. Inasmuch as the friction drag device 35, 37 resists rotation of the outer and inner sleeves 25, 26, such rotation produces a downward feeding of the outer sleeve 25, and also of the inner sleeve 26, along the body 10 by virtue of the lefthand threaded connections 30, 31 and 33, 34. However, since the threaded connection 33, 34 between the outer sleeve 25 and body 10 has only one-half the lead of the threaded connection 30, 31 between the inner sleeve 26 and body, the latter sleeve moves downwardly twice the distance of the outer sleeve 25. Rotation of the casing string and body a predetermined number of revolutions will dispose the inner sleeve valve 26 below the inner ports 24 to open them for the passage of fluid and permit such fluid to flow through the inner ports 24 and out through outer ports 48 provided in the outer sleeve immediately below its tapered seat 43 (see Fig. 2). During such downward movement of the inner sleeve member 26 to port opening position, the outer sleeve 25 has only moved downwardly from its initial position to a slight extent, or only one-half the distance which the inner valve member has moved downwardly. The initial location of the outer sleeve member ports 48 is such as to produce opening of the inner sleeve 26 to its fullest extent before the outer sleeve 25 can close the inner ports 24 against passage of fluids.

A second charge of cement slurry may now be pumped downwardly through the casing string for outward passage through the inner and outer ports 24, 48 and for upward flowing through the annulus around the casing string. Following the ejection of the required amount of the second charge of cement slurry, the casing string may again be rotated to the right to produce a continued downward feeding of the inner sleeve 26 and outer sleeve 25. However, the threads 30 on the inner sleeve become disengaged from the body threads 31, and the former drops downwardly to a slight extent until it rests upon the body shoulder 32, which precludes its further downward movement upon rotation of the body 10. The outer sleeve valve 25 continues its downward travel until its inclined valve seat 43 again engages the tapered head 42 at the upper end of the inner sleeve 26, which effects a complete closing of the inner ports 24 against flow of fluids in both directions between the interior and exterior of the apparatus. When in this position, leakage cannot occur through the ports 24 in view of the three seals furnished by engagement of the upper seal ring 45 with the outer sleeve 25, of the

lower seal ring 46 with the inner sleeve valve 26, and the longitudinally contacting seal 44 between the outer sleeve 25 and inner sleeve 26.

The apparatus may be used without the lower swivel D in the event that cement slurry is not discharged from a lower point in the casing string. Under such circumstances, the entire casing string is rotated without rotating the inner and outer sleeve members 25, 26, whose turning is resisted by engagement of the drag springs 27 against the wall of the formation. The rotation of the casing string in the same direction moves the sleeve members from their port closing position to port opening position, and then to port closing position once more. The provision of the lefthand threaded connections 30, 31 and 33, 34, in order to obtain downward feeding of the sleeve valves 25, 26, enables the casing string to be turned to the right, thereby avoiding any tendency for unscrewing of the casing sections at the coupling collars or casing joints.

It is to be noted that none of the seals 44, 45, 46 is moved past any of the ports 24, 48, nor are any ports moved past such seals, which motion might tend to cut the seals and introduce leakage into the apparatus. The side seals 45, 46 on opposite sides of the ports 24 are always in engagement with smooth cylindrical surfaces on the outer sleeve 25 and inner sleeve 26, and the head seal 44 does not move slidably past the ports 24, since it is spaced outwardly therefrom.

The entire apparatus has an internal diameter which is no less than the internal diameter of the casing string, enabling the usual cementing plugs to be pumped completely through the apparatus when displacing the lower charge of cement slurry from the casing string. It is also to be noted that the outside diameter of the apparatus is little more than the diameter of the usual couplings connecting the various casing sections together, allowing the apparatus to be run in well bores whose outside diameter is very little more than the outside diameter of the casing string itself. It is further to be noted that the drag springs 37, in addition to performing their function of resisting rotation of the outer sleeve 25 and inner sleeve 26, also act as a centralizer for the apparatus and casing string, centering the casing in the well bore and insuring the deposition of a uniform body of cementitious material around the collar apparatus and casing string.

Having thus described my invention, what I claim and desire to secure by Letters Patent is:

1. Apparatus of the character described, including a tubular body adapted to form part of a casing string, said body having a side port, first and second sleeves on said body for controlling flow of fluid through said port, first and second connections between said body and said first and second sleeves, respectively, for effecting movement of said first and second sleeves relative to each other longitudinally along said body to open and close said port upon relative rotation between said body and sleeves, and means engageable with said sleeves for enabling such relative rotation between said body and sleeves to occur.

2. Apparatus of the character described, including a tubular body adapted to form part of a casing string, said body having a side port, first and second sleeves on said body for controlling flow of fluid through said port, first and second connections between said body and said first and second sleeves, respectively, for effecting move-

ment of said first and second sleeves different longitudinal distances along said body to open and close said port upon relative rotation between said body and sleeves, and means engageable with said sleeves for enabling such relative rotation between said body and sleeves to occur.

3. Apparatus of the character described, including a tubular body adapted to form part of a casing string, said body having a side port, first and second sleeves on said body for controlling flow of fluid through said port, first and second connections between said body and said first and second sleeves, respectively, for effecting movement of said first and second sleeves relative to each other longitudinally along said body to open and close said port upon rotation of said body, and means for resisting rotation of said sleeves to enable said body to rotate with respect to said sleeves.

4. Apparatus of the character described, including a tubular body adapted to form part of a casing string, said body having a side port, first and second sleeves on said body for controlling flow of fluid through said port, first and second connections between said body and said first and second sleeves, respectively, for effecting movement of said first and second sleeves different longitudinal distances along said body to open and close said port upon rotation of said body, and means for resisting rotation of said sleeves to enable said body to rotate with respect to said sleeves.

5. Apparatus of the character described, including a tubular body adapted to form part of a casing string, said body having a side port, first and second sleeves on said body for controlling flow of fluid through said port, first and second connections between said body and said first and second sleeves, respectively, for effecting movement of said first and second sleeves different longitudinal distances in the same direction along said body to open and close said port upon relative rotation between said body and sleeves, and means engageable with said sleeves for enabling such relative rotation between said body and sleeves to occur.

6. Apparatus of the character described, including a tubular body adapted to form part of a casing string, said body having a side port, first and second sleeves on said body for controlling flow of fluid through said port, a first threaded connection between said body and said first sleeve and a second threaded connection between said body and said second sleeve having a different lead from the lead of said first threaded connection, whereby relative rotation between said body and sleeves effects movement of said sleeves different longitudinal distances along said body to open and close said port, and means engageable with said sleeves for enabling such relative rotation between said body and sleeves to occur.

7. Apparatus of the character described, including a tubular body adapted to form part of a casing string, said body having a side port, first and second sleeves on said body for controlling flow of fluid through said port, a first threaded connection between said body and said first sleeve, a second threaded connection between said body and said second sleeve having a different lead from the lead of said first threaded connection, and means for resisting rotation of said sleeves when said tubular body is rotated, whereby rotation of said body effects movement of said sleeves different longitudinal distances along said body to open and close said port.

8. Apparatus of the character described, including a tubular body adapted to form part of a casing string positionable in a well bore, said body having a side port, first and second sleeves on said body for controlling flow of fluid through said port, means providing a slidable splined connection between said sleeves, a first threaded connection between said body and said first sleeve, a second threaded connection between said body and said second sleeve having a different lead from the lead of said first threaded connection, and means secured to one of said sleeves and adapted to engage the wall of the well bore to resist rotation of said sleeves, whereby rotation of said body effects movement of said sleeves different longitudinal distances along said body to open and close said port.

9. Apparatus of the character described, including a tubular body adapted to form part of a casing string, said body having a side port, first and second sleeves on said body for controlling flow of fluid through said port, a first threaded connection between said body and said first sleeve, a second threaded connection between said body and said second sleeve of the same hand as said first threaded connection but having a different lead from the lead of said first threaded connection, and means for resisting rotation of said sleeves when said tubular body is rotated whereby rotation of said body effects movement of said sleeves different longitudinal distances along said body to open and close said port.

10. Apparatus of the character described, including a tubular body adapted to form part of a casing string, said body having a side port, first and second sleeves on said body for controlling flow of fluid through said port, means providing a slidable splined connection between said sleeves, a first threaded connection between said body and said first sleeve, a second threaded connection between said body and said second sleeve of the same hand as said first threaded connection but having a different lead from the lead of said first threaded connection, and means for resisting rotation of said sleeves whereby relative rotation between said body and sleeves effects movement of said sleeves different longitudinal distances along said body to open and close said port.

11. Apparatus of the character described, including a tubular body adapted to form part of a casing string, said body having a side port, a first sleeve on said body disposed initially across said port to close the same, a first threaded connection between said body and said first sleeve, a second sleeve on said body slidably splined to said first sleeve, a second threaded connection between said body and said second sleeve of the same hand as said first threaded connection but having a different lead from the lead of said first threaded connection, and means engageable with said sleeves for enabling relative rotation between said body and sleeves to first effect relative longitudinal movement of said first sleeve along said body to port opening position and then to move said second sleeve along said body to port closing position.

12. Apparatus of the character described, including a tubular body adapted to form part of a casing string positionable in a well bore, said body having a side port, a first sleeve on said body disposed initially across said port to close the same, a first threaded connection between said body and said first sleeve, a second sleeve

10 on said body slidably splined to said first sleeve, a second threaded connection between said body and said second sleeve of the same hand as said first threaded connection but having a different lead from the lead of said first threaded connection, and means secured to said second sleeve and engageable with the wall of the well bore for resisting rotation of said sleeves, whereby rotation of said body first effects longitudinal movement of said first sleeve along said body to port opening position and then moves said second sleeve along said body to port closing position.

13. Apparatus of the character described, including a tubular body adapted to form part of a casing string positionable in a well bore, said body having a side port, a first sleeve on said body disposed initially across said port to close the same, a first threaded connection between said body and said first sleeve on one side of said port, a second sleeve on said body having a side port communicable with said body port and slidably splined to said first sleeve, a second threaded connection between said body and said second sleeve on the other side of said body port, said second threaded connection being of the same hand as said first threaded connection but having a different lead from the lead of said first threaded connection, and means secured to said second sleeve and engageable with the wall of the well bore for resisting rotation of said sleeves, whereby rotation of said body first effects longitudinal movement of said first sleeve along said body to body port opening position and unthreads said first sleeve from said body to establish communication between said body port and side port, a continuation of the rotation of said body in the same direction then moving said second sleeve along said body into engagement with said first sleeve to close said body port.

14. Apparatus of the character described, including a tubular body adapted to form part of a casing string positionable in a well bore, said body having a side port, a first sleeve on said body disposed initially across said port to close the same, a first threaded connection between said body and said first sleeve, a second sleeve on said body slidably splined to said first sleeve and having a side port communicable with said body port, a second threaded connection between said body and said second sleeve of the same hand as said first threaded connection but having a different lead from the lead of said first threaded connection, and means secured to said second sleeve and engageable with the wall of the well bore for resisting rotation of said sleeves, whereby rotation of said body first effects longitudinal movement of said first sleeve along said body to body port opening position to establish communication between said ports and then moves said second sleeve along the said body to body port closing position.
